(57) **CLAIM**

The ornamental design for a biomedical monitoring headset as shown and described.

DESCRIPTION

FIG. 1 is a perspective view including the front, top, and side of an embodiment of a biomedical monitoring headset; FIG. 2 is a perspective view including the rear, bottom, and side of the biomedical monitoring headset of FIG. 1; FIG. 3 is a front elevation view of the biomedical monitoring headset of FIG. 1; FIG. 4 is a rear elevation view of the biomedical monitoring headset of FIG. 1; FIG. 5 is a side elevation view of the biomedical monitoring headset of FIG. 1; FIG. 6 is an opposite side elevation view of the biomedical monitoring headset of FIG. 1; FIG. 7 is a top plan view of the biomedical monitoring headset of FIG. 1; FIG. 8 is a bottom plan view of the biomedical monitoring headset of FIG. 1; and, FIG. 9 is a front elevation view of the biomedical monitoring headset of FIG. 1 shown in a configuration of use. The broken lines are directed to environmental structure and unclaimed subject matter and are for illustrative purposes only; the broken lines form no part of the claimed design. In FIG. 9, the broken lines are for the purpose of illustrating environment only and form no part of the claimed design.
